UNITED STATES PATENT OFFICE.

WALTER HAHNEMANN, OF KITZEBERG, NEAR KIEL, GERMANY, ASSIGNOR TO C.
LORENZ AKTIENGESELLSCHAFT, OF BERLIN-TEMPELHOF, GERMANY.

ARRANGEMENT FOR UNIFORM ELECTRICAL SOUND TRANSMISSION.

Application filed March 24, 1926, Serial No. 97,008, and in Germany March 31, 1925.

The invention deals with the problem of providing a sound apparatus which carries out the transformation of mechanical sound energy from and into electric energy as faithfully as possible within an extraordinary large range of frequencies, that is to say, it is to be so constructed that the different sound oscillations which are present in a large complex (for example, in the transformation of music) are transformed and reproduced perfectly, both as regards the absolute magnitude of the sound oscillations on the one hand and above all with regard to their relative loudness of tone on the other hand.

With a view to solving this problem it has already been proposed to permit different, constructively independent, transmitting or receiving devices to cooperate with one another, each of them having allotted to it a predetermined range of frequency so that the frequency ranges of the individual, constructively independent, oscillation systems are grouped or located adjacent to one another in any desired arrangement, and so that the whole spectrum of audible frequencies is continuously covered. At the same time the individual vibratory systems themselves may be composed of several individual oscillatory structures so that they constitute coupled systems, whose coupling resonance regions are arranged in a row within the frequency range allotted to the individual oscillators.

It has been found that if loud speaking electrical oscillators of the same type are used in such systems, in spite of having equal efficiency, high and low frequencies are reproduced with different strengths because the so-called efficiency-constant of these devices is dependent upon the frequency.

According to the invention for the three principal ranges of high, medium and low frequencies, the three different, possible types of apparatus can be used at the same time, namely, the electrostatic apparatus, the electromagnetic apparatus and the electrodynamic apparatus, the electrostatic apparatus being allotted to the transformation and reproduction of the high frequencies, the electrodynamic apparatus being allotted to the transformation and reproduction of the low frequencies and the electromagnetic apparatus being allotted to the transformation and reproduction of the medium fre-

quencies. The electrostatic apparatus is particularly suitable for use with high frequencies, compared with the electromagnetic and the electrodynamic devices which work with iron, because with increasing frequency 60 the dielectric losses increase considerably more gradually than the iron losses. The electrodynamic apparatus on the other hand compared with the electromagnetic is more suitable for lower frequencies than the latter 65 apparatus is, because the efficiency-constant of the electromagnetic apparatus increases or diminishes with the square of the frequency whilst the efficiency-constant of the electrodynamic apparatus only varies with 70 the first power of the frequency.

A further feature of the invention consists in the different degree of efficiency of the different individual electrical vibrators being balanced by the inverse degree of amplification in connection with the different types. This feature may be applied in connection with apparatus of different type or with apparatus of the same type.

The efficiency-constant represents, as is 80 well-known from the work of Hahnemann and Hecht (see particularly "Physikalische Zeitschrift" 20, 1919, Schallgeber und Schallempfänger, I), a measure for the efficiency of the apparatus and the formulae 85 for this constant are the following:

For the electromagnetic principle:

$$K_m = \frac{d\eta}{1-\eta} \omega^2 m$$

For the electrodynamic principle:

$$K_d = \frac{d\eta}{1-\eta} \omega m.$$

In Figures 1-3 constructional examples of 95 the invention are shown.

Figure 1 shows the application of three different types of electric apparatus, namely for high frequencies the electrostatic apparatus, for medium frequencies the electromagnetic apparatus, for low frequencies the electrodynamic apparatus in combination with suitable circuit arrangements appropriate to the different ranges of frequency.

Figure 2 shows a practical example of the 105 invention with three transmitters of the same kind, namely, transmitters according to the condenser principle, which, in order to indicate their different tuning are chosen of different size and according to the guid-

ing principles set out in the beginning are provided with amplifying sets whose degree of amplification falls as the frequency increases.

5 Figure 3 shows a corresponding arrangement with electrodynamic oscillators, in which also in accordance with the guiding principles explained before, the degree of amplification of the amplifying devices connected therewith increase in the direction of higher frequencies.

10 In all the figures the reference numeral 1 indicates a sound horn which is coupled with the resonator 2. An oscillatory diaphragm 15 3 abuts on the resonator 2. This diaphragm carries in the case of the condenser apparatus the one plate 4 of the pair of condenser plates, in the case of the electromagnetic apparatus the armature 5 and in the 20 case of the electrodynamic apparatus the oscillating current conductor 6. The second condenser plate in the condenser apparatus is indicated by 7, the magnetic structure of the electromagnetic apparatus by 8 and the 25 magnetic structure of the electrodynamic apparatus by 9. For the high frequencies a chain of series condensers and shunt inductances which substantially filters out the low frequencies is connected in front of the apparatus associated therewith. For the low 30 frequencies a chain 11 composed of series choke coils and shunt condensers, which substantially shuts out the higher frequencies, is connected in front of the apparatus associated therewith. For the apparatus of the 35 medium range of frequency a mixed chain 12, composed of both series and shunt condensers and choke coils, is provided. V_1 , V_2 , V_3 are amplifier units, the degree of 40 amplification of each unit being assumed to be the same.

The invention may be used with equal advantage for receiving and reproducing apparatus of the smallest and the greatest 45 dimensions.

In this specification the term sound receiver is used in the true sense as a sound "pick-up" and the term sound transmitter as a sound emitter or "loud speaker."

50 I claim:—

1. A device for sound communication comprising a plurality of individual electrical vibrators; a vibrator of the electrostatic type for the high frequency range, a vibrator of the electromagnetic type for the medium 55 frequency range, and a vibrator of the electrodynamic type for the low frequency range.

2. A device for sound communication comprising electrical vibrators of different 60 type for different ranges of frequencies; a vibrator of the electrostatic type for the high frequency range, a vibrator of the electromagnetic type for the medium frequency range, and a vibrator of the electrodynamic 65 type for the low frequency range; and a high frequency pass filter circuit connected to the electrostatic vibrator, a medium frequency pass filter circuit connected to the electromagnetic vibrator, and a low frequency pass filter circuit connected to the 70 electrodynamic vibrator.

3. A device for sound communication comprising a plurality of electrical vibrators for the different ranges of frequencies, and amplifiers of different degree of amplification connected to the individual vibrators in the inverse ratio of the efficiency of production of sound of the individual vibrators.

75 In testimony whereof I affix my signature.

WALTER HAHNEMANN.
